UNITED STATES PATENT OFFICE.

FRANCIS THREM, OF CINCINNATI, OHIO.

BUNG.

SPECIFICATION forming part of Letters Patent No. 350,402, dated October 5, 1886.

Application filed August 23, 1886. Serial No. 211,623. (No model.)

To all whom it may concern:

Be it known that I, FRANCIS THREM, a citizen of the United States, residing at Cincinnati, in the county of Hamilton, State of Ohio, have invented certain new and useful Improvements in Bungs, of which the following is a specification, reference being had therein to the accompanying drawings.

My invention consists in a wooden bung 10 constructed in such a manner as to permit the ready insertion therein either of a large or small air-vent instrument, the improvement being susceptible of a number of changes or modifications, as hereinafter more fully described.

In the annexed drawings, Figure 1 is a plan of the upper end of my preferred form of bung. Fig. 2 is a plan of the lower end thereof. Fig. 3 is an axial section of said bung. Figs. 20 4, 5, 6, and 7 are similar sections of four modifications of my invention.

A represents an ordinary wooden bung, the upper end of which has an annular incision, B, made therein, which cut may be carried 25 down as far as desired.

C is an annular incision in the lower end of the bung, and extending up into the same a sufficient distance. This incision C is preferably concentric with the cut B, but of some- 30 what greater diameter than the latter. Furthermore, the cylindrical plug D, surrounded by the incision B, is either compressed or cut down so as to bring its top below the upper surface of the bung proper, in order that said 35 plug may not be struck by the mallet used in driving said bung into a key or barrel; but the cylindrical plug E, surrounded by the lower incision, C, need not be reduced in length.

The bung as above described is known to 40 be old, and in using the same the heel of the air-vent is placed upon the plug D, and a moderate blow against the upper end of the instrument tears apart the thin web F remaining between the incisions B C, and thus per- 45 mits the insertion of said vent. It is evident, however, that the air-vent heel must be practically of the same diameter as the upper incision, B, or a tight joint will not be afforded. It is also apparent that a vent of less diameter 50 than said incision could not be used, and, as a number of these instruments are comparatively small, some provision is needed for their in-

sertion in the bung. I accordingly make a bore, d, in the upper plug, D, and a similar bore, e, in the lower plug, E, and separate them 55 by a thin web, H, which provision of said devices d e H allows a comparatively small air-vent to be used. With such a vent it is necessary only to employ sufficient force to rupture the web H in the act of inserting the instrument, the tubular stem or shank of which occupies the now communicating bores d and e; hence, it is apparent a bung constructed in this manner will admit two different-sized air-vents, thereby greatly increasing the utility 65 of the device.

Having thus suggested the idea of a bung capable of admitting different-sized air-vents, modifications of the invention can be devised with very little trouble. One obvious change 70 is seen in Fig. 4, where a single continuous bore, I, is made in the bung, which bore begins at the upper end of the plug D and terminates at bottom with the web H; but in Fig. 5 a continuous bore, J, is made from the 75 bottom of the bung, and is carried up almost to the top of the same, being closed by the web H. Furthermore, the upper end of plug D may be countersunk, as at h, to indicate the exact place where the air-vent heel is to be 80 applied for the purpose of breaking through the web H, and thereby traversing the afore- said bore J.

Fig. 6 shows a bung having an upper annular incision, B, and plug D, which latter has 85 a bore, K, open at its upper end, but closed at bottom by the web H.

Another modification of the invention is seen in Fig. 7, where the bung has a lower annular incision, C, and at top a chamber, L, 90 from the bottom of which latter proceeds a bore, M, closed by the web H.

It will be noticed that the bungs seen in Figs. 4, 5, 6, and 7 are similar to the device shown in Fig. 3, inasmuch as they afford facilities for the insertion either of a large or small air-vent of any construction.

I claim as my invention—

1. A bung having an annular incision extending partially through it to afford a plug, 100 which latter is traversed by a bore closed at one end with a web, whereby said bung admits two different-sized air-vents, substantially as herein described.

2. A bung having upper and lower annular incisions extending partially through it to afford a pair of plugs, each of which is traversed by a bore separated by a web, whereby said bung admits two different-sized air-vents, substantially as herein described.

3. A bung having upper and lower annular incisions extending partially through it to afford a pair of plugs, traversed by a single bore proceeding from the bottom of said bung

and closed at top by a web, the upper surface of the latter being countersunk, for the purpose described.

In testimony whereof I affix my signature in presence of two witnesses.

FRANCIS THREM.
